UNITED STATES PATENT OFFICE.

JOSEPH NEMETH, OF ST. LOUIS, MISSOURI.

HAT-PIN GUARD.

1,074,735.

Specification of Letters Patent.

Patented Oct. 7, 1913.

Application filed March 13, 1913. Serial No. 754,010.

To all whom it may concern:

Be it known that I, JOSEPH NEMETH, a subject of Francis Joseph, Emperor of Austria and Apostolic King of Hungary, residing at the city of St. Louis, State of Missouri, have invented certain new and useful Improvements in Hat-Pin Guards, of which the following is a specification, reference being had to the accompanying drawings, forming a part hereof, in which—

Figure 1 is an elevational view of my new hat-pin guard, the same being shown in operative position on a hat-pin; Fig. 2 is a similar view somewhat enlarged, the 15 hat-pin being broken away; Fig. 3 is a longitudinal sectional view through my new hat-pin guard; Fig. 4 is a longitudinal sectional view through my new hat-pin guard on approximately line 4—4, Fig. 3; Fig. 5 20 is a transverse sectional view on line 5—5, Fig. 2; Fig. 6 is a transverse sectional view on line 6—6, Fig. 2; and Fig. 7 is a front end view of my new hat-pin guard.

This invention relates to certain new and 25 useful improvements in hat-pin guards and, more particularly, to a certain new and useful device or article of manufacture adapted to removably inclose the pointed or sharpened end of a hat-pin or the like when 30 in use and thereby not only obviate the possibility of personal injury from or by the pin when in operative position in a hat or the like, but also prevent the accidental or surreptitious withdrawal of the pin from 35 such position, the objects of my invention being to provide a device of the kind stated of simple, cheap construction and which may be readily, easily, and quickly placed into, and, when desired or necessary, re- 40 moved from, operative position upon or in engagement with a hat-pin or the like, and to improve generally upon articles of the kind described.

With the above objects in view, my invention resides in certain novel features of construction, arrangement, and combination of parts, all as will hereinafter be described and afterward pointed out in the claims.

In the accompanying drawings, A indicates the body portion of my new hat-pin guard, which is in the form preferably of an elongated metallic shell or casing having a preferably rectangular rear wall 1, a substantially flat somewhat tapering top or upper wall 2, a lower or bottom wall having a flat portion 3 and an upwardly inclined

tapering portion 3', and tapering side walls 4—4, said upper, lower, and side walls merging at their forward end into an outwardly flaring circular pin-opening 5 of suitable 60 diameter leading into the interior of shell A adjacent the under face or surface of its top wall 1, as shown particularly in Figs. 4 and 7.

Arranged within shell or casing 1 is a pin 65 guide-member preferably integrally comprising a portion 6 extending lengthwise with and upon lower wall portion 3, a flanged upwardly projecting portion 7 fitting against rear wall 1 and centrally cut away 70 at its upper end to provide a recess or groove, as at 8, in alinement with opening 5 of casing or shell A, a portion 9 extending obliquely upwardly adjacent lower wall portion 3', and an extension 10 projecting forwardly within the tapering portion of casing or shell A and provided at its forward end with a rearwardly bent portion 11 centrally cut away to provide a recess or groove, as at 12, also substantially in alinement with 75 pin-opening 5 of shell A. Adjacent its rear end and also adjacent one of said side walls 4, as shown particularly in Fig. 2, top or upper wall 2 of casing or shell A is provided with an elongated slot in which mov- 80 ably fits the bight 13 of a spring-depressing member B substantially U-shaped in cross section, one leg thereof, which we will call its upper leg 14, lying outside of shell A and extending substantially flatwise relatively to top or upper wall 2 and the other or lower leg thereof 15 lying within shell A and similarly extending substantially flatwise relatively to top or upper wall 2 there- 85 of. Interposed between lower leg 15 of member B and portion 6 of said pin guide member is a coiled spring or the like 16 adapted normally to maintain said member B in outermost position with the upper face of its lower leg 15 flatwise against the lower 90 face of top or upper wall 2. As shown particularly in Figs. 4 and 5, one end of spring 16 is preferably suitably attached to lower leg 15 of member B to maintain 95 said parts in operative relation within shell A.

In operation, when it is desired to arrange my new hat-pin guard in operative position upon a pin or the like P, upper leg 14 of member B is first engaged by a thumb or 100 finger to resiliently depress its lower leg 15 away from wall 2. Pin P, being then in-

serted into shell A through opening 5, will be guided by said alining grooves 8 and 12 of said guide-member to between said leg 15 and wall 2. Member B being then released, 5 said lower leg 15 will, under the resiliency of spring 16, coöperate with wall 2 of shell or casing A to frictionally engage the pin P therebetween, my new hat-pin guard being thereby removably held in operative position 10 upon the pin.

While I have herein shown and described my new pin-guard in connection with a hat-pin, and for which use it is especially designed and adapted, yet it is to be understood 15 that it may equally well be employed in connection with scarf-pins and the like and that minor changes in the construction, arrangement, and combination of the several parts thereof may be made and substituted for those herein shown and described without departing from the nature and principle of my invention.

Having thus described my invention, what I claim and desire to secure by Letters 25 Patent is:

1. In a device of the kind described, an elongated casing having a pin-opening at one end, the upper wall of said casing being provided with a slot, a substantially U-shaped member having its bight movably fitting in said slot and its legs disposed on opposite sides of said wall, and a spring interposed between the opposite wall of said casing and the lower leg of said member, the 30 lower leg of said member being adapted to coöperate with the upper wall of said casing to frictionally engage a pin or the like therebetween; substantially as described.

2. In a device of the kind described, an 40 elongated casing having a pin-opening at

one end, the upper wall of said casing being provided with a slot, a substantially U-shaped member having its bight movably fitting in said slot and its legs disposed on opposite sides of said wall, a spring interposed 45 between the opposite wall of said casing and the lower leg of said member, the leg of said member within said casing being adapted to coöperate with the upper wall of said casing to frictionally engage the pin or the like therebetween, and a member within 50 said casing adapted to guide the pin or the like between said leg and casing-wall; substantially as described.

3. In a device of the kind described, an elongated casing having a pin-opening at 55 one end, the upper wall of said casing being provided with a slot, a substantially U-shaped member having its bight movably fitting in said slot and its legs disposed on opposite sides of said wall, the leg of said member within said casing being adapted to coöperate with the upper wall of said casing to frictionally engage a pin or the like therebetween, a member within said casing adapted 60 to guide the pin or the like between said leg and casing-wall, said guide-member having a portion extending lengthwise with and upon the opposite wall of said casing, and a coiled spring interposed between said guide-member-portion and said leg of said U-shaped member; substantially as described. 65

In testimony whereof, I have signed my name to this specification, in the presence of two subscribing witnesses.

JOSEPH NEMETH.

Witnesses:

JOSEPH HANNA,
ZELMA PINCUS.
